FLUID HEAT EXCHANGE APPARATUS

Perry R. Cassidy, Short Hills, N. J. assignor to
 The Babcock & Wilcox Company, Newark, N. J.,
 a corporation of New Jersey

Application September 20, 1935, Serial No. 41,403

8 Claims. (Cl. 122—478)

This invention relates to fluid heat exchange apparatus, and it is exemplified herein in connection with water tube steam boilers.

More particularly, the invention comprehends improvements in steam boilers of the bent tube type, with which superheaters are associated.

It is an object of the invention to provide a boiler which will generate steam at high capacities without impairment of the quality or superheat of the steam, or integrity of the superheater. High steam quality as to purity is attained by reason of the relation of the disengaging surfaces of the water to the saturated steam exit in the separator chamber of the boiler. High superheat is also attained with a minimum of superheater surface by improving the transverse mass flow (mass flow being authoritatively and widely known as weight of gases per unit of area, per unit of time, weight rate of flow; Chemical Engineering Handbook, J. H. Perry, 1934 edition page 736, McGraw Hill Publishing Company, New York, N. Y.; Kent's Mechanical Engineer's Handbook, eleventh edition, volume II, 1936, page 6-45, John Wiley & Sons, Publishers; American Standard Association, "Letter Symbols for Heat and Thermodynamics including Heat Flow—H. F.," October 1939, page 7) of high temperature gases over that surface, and the integrity of the superheater is maintained by a radiant heat screen and drainage of water from it.

It is also an object of the invention to improve the effectiveness of heat transfer in a multiple separator boiler by providing for the most effective flow of the furnace gases transversely of the vertically disposed steam generating tubes, and this reduces the cost of the boiler per unit of capacity.

A further object of the invention is an improvement in such boilers wherein ratio of the cost of the superheater to the cost of the total installation is reduced, with no consequent loss in effectiveness.

Other objects of the invention relate to water tube steam boilers in which a single lower drum is joined by separate banks of upright tubes to a plurality of upper drums. These banks of tubes extend entirely across the width of the boiler, and the general combination is such that natural tendencies toward priming and the production of steam under high capacity operating conditions are overcome. The steam separation takes place finally in an offtake drum increasingly effective as the boiler capacity increases so that the production of dry steam is maintained. The steam and water separation is a multiple

stage separation taking place in different stages in the upper drums as a considerable portion of the steam generated passes through the drums in succession to a steam outlet which is on the rear drum.

The invention comprehends a multiple tube bank water steam boiler in which the front bank of tubes receives gases from a furnace across the entire width of the boiler and in a single gas pass. It discharges the gases rearwardly into a gas equalization space extending also across the entire width of the boiler. Thus, substantially uniform gas distribution across the front bank is effected, regardless of the direction of firing, or of the type of furnace used.

A slag screen may also be advantageously provided by the front bank of the tubes, and, to this end, some of the tubes of the front bank are more widely spaced. If the firing of the furnace is from the side, the gases would concentrate toward one end and thus tend to cause an unequal flow across the front bank. The invention comprehends, as one means for neutralizing such an effect, a tapering free gas flow space from side to side of the boiler, in the front bank. This is provided by a tapering baffle.

The space at the rear of the front bank of tubes is made wide enough to contribute to gas distribution and equalization across the front bank and the gases enter this space across the entire width of the boiler in a generally horizontal direction at the front of the space. They leave it rearwardly over a portion only of the width of the boiler, and the relationship of elements effecting this action would have a natural tendency to cause some of the gases in front of the exit for the equalization space to flow straight across that space while gases at the other end of the space would be compelled to approach the exit by side to side flow. If the equalization space did not have sufficient width such side to side flow would tend to disturb distribution of the gases across the front bank even with front firing and thus tend to concentrate the gas flow through that portion directly in front of the exit from the space. This could be corrected, with a narrow space, by such front bank distribution baffles as have been mentioned, but by making the space sufficiently wide the side to side gas flow through the space takes place at a low velocity and uniform distribution in the front bank may be effected without such distribution baffles, therefore making for a saving in draft loss and keeping all front tube surface equally effective at high capacities.

To effect the above described gas flow and to control gas flow in the inter-tube bank spaces, an angle baffle is provided. One leg of this baffle forms a back wall of the above described gas equalization space, and the other leg bounds the gas pass which forms the exit from that space. This baffle cooperates with another straight baffle to provide three gas passes extending forwardly or rearwardly across the tube bank from side to side, the first starting at the exit from said space, and the gases being forced to flow in a generally horizontal direction throughout the boiler. The boiler, as above described, may be considered as having a tapering first gas pass, including the whole front bank at its wide part, and the invention comprehends a superheater which is located in a narrow part of that gas pass between the first and second bank of tubes. The arrangement improves mass flow over the superheater by giving it a high value and equalizing it to the end that variations in the superheat from a desirable flat curve will be minimized as the boiler is operated at increasing capacity.

Other objects of the invention will appear as the accompanying description proceeds.

Fig. 1 is a view in the nature of a vertical section, showing a water tube steam boiler and its furnace together with the relationship of the superheater to the steam generating tubes. This view is taken on the line 1—1 of Fig. 3.

Fig. 2 is a vertical sectional view taken on the line 2—2 of Fig. 3.

Fig. 3 is a horizontal section taken on the line 3—3 of Fig. 2. This view shows the relationship of the different gas passes to the superheater and to the steam generating tubes.

Fig. 4 is a view in the nature of a front elevation of the front bank of steam generating tubes, showing a tapered baffle for effecting distribution of gas flow across the steam generating tubes of the first bank. In a cut-out portion, a part of the superheater construction is shown.

Fig. 5 is a view in the nature of a vertical section showing a modified boiler construction in which the first section of the superheater extends entirely across the width of the boiler.

Fig. 6 is a section taken on the line 6—6 of Fig. 5.

Fig. 7 is a detailed view in the nature of a vertical section showing the manner in which the horizontal manifolds of the Fig. 1 superheater may be arranged and supported.

Fig. 8 is a vertical section taken in a plane as indicated by the line 8—8 of Fig. 7.

Fig. 9 is a view in the nature of a vertical section showing a modified arrangement of parts involved in the location of the superheater manifolds.

Fig. 10 is a view in the nature of an upright section taken on the line 10—10 of Fig. 9.

The drawings indicate bent tube steam boilers each having a lower drum 10 connected to the steam and water drums 12 and 14 by banks of steam generating tubes. In each illustrative embodiment of the invention the tubes of the front bank 16 extend forwardly of the drum 10 adjacent the combustion chamber 18 of a furnace. Tubes connected to the rear drum 12 are disposed rearwardly of a superheater 20, relative to gas flow.

Referring to Fig. 3 of the drawings, the furnace gases from the combustion chamber 18 first pass over and between the tubes of the bank 16 into an equalizer chamber 22. From this chamber they are compelled by the baffles 24 and 26 to pass

across the tubes of the superheater 20 and rearwardly of the boiler through the first gas pass defined by the baffle 26 and the wall 23 of the boiler. After passing over the tubes of the superheater the gases pass over and between the tubes 30 which form a part of the bank connecting the drums 10 and 12.

From the outlet 32 of the first gas pass the gases proceed to the inlet 34 of the second gas pass through which the gases proceed forwardly 10 through the banks of steam generating tubes 36 and 38. This second gas pass is formed between the baffles 26 and 40, the latter extending forwardly from the rear wall 42 of the boiler.

After passing across the bank of tubes 38 in 15 the second pass the furnace gases turn in the space 44 rearwardly of the wall 24 and enter the third gas pass in which they proceed rearwardly across the tubes and then upwardly to a flue 45. The flow of gases through this flue may be controlled by dampers 46 and 48.

In connection with the above indicated structure, it will be noted that open spaces are provided at the positions where the gases turn from one gas pass into another. This facilitates the 25 changes in direction of the gases and is advantageous for two particular reasons, first, that draft loss incident to the turning of the gases is minimized, and second, that uniform distribution across the tubes in the different gas passes is effected.

It will also be noted, in the illustrative boiler, that the gases have a generally horizontal flow and that they change their directions at the same level. The tubes contacted by the horizontally 35 moving gases are preferably inclined and these circumstances facilitate the deposition and removal of solids carried by the gases. They may fall out of the gas stream into pockets from which they may be conveniently removed. This promotes the maintenance of clean heating surfaces.

The fact that the tubes of the front and rear bank are inclined as shown is advantageous. Referring to the inclination of the front bank, the space between the front furnace wall and 45 the tubes of the front bank constitutes a part of the furnace space, and the gases rising into this triangular space are well distributed over the tubes of the bank. Also, this arrangement includes tubes which extend over the top of the 50 furnace so that they are directly exposed to radiant heat. With this arrangement also, wall cooling tubes may be conveniently added and connected into the boiler circulation, thus giving a completely water cooled furnace top with a 55 tapering gas pass to promote uniform distribution of gas flow across the tubes of the front bank. Referring to the inclination of the rear bank with respect to the rear wall of the boiler, gas flow to an exit flue connection from the last 60 gas pass and at the upper rear part of the boiler is facilitated.

Although the illustrative embodiments include but two steam and water drums, it is to be understood that these embodiments are only representative, and that a greater number of steam and water drums and connecting banks of steam generating tubes may be employed. In any event the gas flow across the successive banks of tubes is of the nature above indicated.

Fig. 4 of the drawings indicates a flow distributor represented as a substantially triangular baffle 50 preferably supported by the tubes 52 of the front bank 16. This baffle may consist of refractory material held in position by metallic 75

studs which are welded to the tubes 52. Its wider end, in a vertical direction, is adjacent to the wall 28 as shown in Fig. 4, and it is located directly in front of the first gas pass. In conjunction with the tubes of the bank 16 it affords upper and lower gas passages through that bank, said passages increasing in flow area as the wall 54 is approached. Short circuiting of the tubes disposed away from the first gas pass and toward the wall 54 is thus minimized and a more uniform distribution of gas contact over the tubes of the first bank is attained.

The superheater disposed in the first gas pass and rearwardly of the wider end of the equalizer baffle 50 may consist of an outlet header 56 supported upon the drum 10 and having manifolds 58 extending forwardly therefrom. The inlet ends of these manifolds are connected to the steam space 60 of the drum 12 by inlet tubes 62. As shown in Fig. 3, these tubes may have a spacing wider than that of the remaining tubes of the superheater, and the entrance of water into these tubes is prevented by a steam and water separator 64.

25 The steam after passing from the drum 12 to the inlet ends of the manifolds 58 through the tubes 62 proceeds in succession through the series of upwardly looped tubes 64, 66 and 68 to the outlet ends of the manifolds. Opposite ends of these looped tubes are connected to separate manifold chambers formed by the partitions 70 as clearly indicated in Figs. 8 and 10. From the rearmost chambers steam proceeds to the outlet header 56 and then to points of use.

35 In Figs. 5 and 6 of the drawings there is illustrated an embodiment in which the superheater is arranged in two sections. The primary section consists of inlet tubes 72 and upwardly looped tubes 74 which are arranged as a bank extending entirely across the furnace. These tubes are connected at their lower ends by the header 76 which is preferably mounted upon a similar header 78 which connects the tubes 74 with the manifolds 80. These manifolds are chambered 40 so as to cause the steam to pass in succession through the series of looped tubes 82 and 84 to the outlet portions of the manifolds and thence to the outlet header 86.

As indicated clearly in Fig. 6 of the drawings, 50 the looped tubes 82 and 84 constituting the second section of the superheater are positioned entirely in the first gas pass at one side of the boiler, this gas pass being formed by the wall 88 and the baffle 90.

55 When the arrangement of elements indicated in Figs. 5 and 6 causes undesirable short circuiting of some of the superheater tubes in the first section and some of the steam generating tubes in the front bank a triangular trickle baffle 60 may be employed. As shown, this baffle consists of refractory elements 92 supported by the tubes 94 and so arranged that alternate inter-tube spaces are closed thereby. In other words, there are small gas passages 96 between the successive elements 92.

Aside from the structures mentioned immediately above, the general arrangement of elements of the entire boiler of the Fig. 6 embodiment is similar to the arrangement described 70 with reference to the Fig. 3 embodiment.

In the illustrative boiler constructions, the upper drums are directly supported upon any suitable steel framework, and the lower drum 10 is mainly supported by the tubes which connect it to the upper drums. When the parts are

arranged in this manner, the lower drum is relatively free to move upwardly or downwardly in response to the temperature changes in the tubes. The outlet header 56 of the superheater is preferably supported upon the lower drum 10 as indicated in Fig. 7 of the drawings. Here, a bracket 130 is secured to lugs 131 attached to the header 56, and is preferably formed at its top to constitute a saddle. The superheater manifolds 58 communicate with the header as shown, and are supported at their outer ends by brackets 132 which may be welded to the tubes 134 of the front bank 16. These brackets are received between pairs of lugs 136 which are rigid with, and depend from, a channel 138 extending across the superheater. As particularly shown in Fig. 8, downwardly extending lugs 140 are bolted to the channel and these lugs are preferably welded to the manifolds 58. In this construction the load of the superheater is distributed over two rows of tubes of the bank 16 by means of struts 142 which are shown as welded to the tubes 134.

In the Fig. 9 construction the load of the manifolds is taken entirely upon the drum 10. The brackets 130 support the header 56 and rear ends of the manifolds, while the forward ends of the manifolds are supported by struts 144 which may be pivoted as indicated at 146 to brackets 148 which are fixed to the drum 10. At the opposite ends of the struts there are pivotal connections to an angle 150 which extends across the manifolds and contact with lugs 152 preferably welded to the forward ends of the manifolds so as to extend downwardly therefrom.

Referring now to other features of the boiler construction indicated in Fig. 1 of the drawings, the lower drum 10 may be pivotally tied to a fixed frame member 154 by means of a link 156 which passes through a bracket 158 rigidly secured to the drum. When the drum is supported in this manner it is free to move upwardly and downwardly as a result of expansion and contraction of the boiler tubes, but it will still be maintained in operative position and be prevented from creating any undesirable side thrust upon the part 160 of the furnace wall which is shown above the header 162.

The boiler furnace may be one in which a burner 164 is employed in connection with the utilization of a slag forming fuel. Molten slag collects on the bottom of the furnace and is periodically tapped through an opening 166.

Walls of the furnace may be fluid cooled as indicated. To provide for such fluid cooling, the headers 162, 168, and 170 at one side of the furnace are preferably connected into the fluid circulation of the boiler. They are also connected by wall tubes 172 and 174. Adequate circulation in these tubes is promoted by exterior circulators 176 which are shown as connecting the headers 162 and 170.

From the header 170 floor cooling tubes 178 extend across the bottom of the furnace and between the wall tubes 180 to a position where they are connected to the header 182. Exterior circulating tubes 184 may connect these headers to the drum 10. The tubes 180 lead from the lower header 186 to an upper header 188 which is connected to the drum 14 by circulator tubes 190 and to the header 186 by tubes 192.

Fluid cooled headers 194 are also provided on the remaining sides of the furnace. They may be connected into the boiler circulation by up-

take tubes 196 and be joined to a lower side wall header by wall tubes 198.

In Fig. 2 of the drawings, a section of the gas distribution baffle 50 is shown at 200. This baffle as well as the wall 24 shown in section at 202 may be of stud tube construction in which the refractory material is maintained, and held in operative position, by metallic studs welded to the tubes.

Fig. 2 also shows a guide for the header 162. This may consist of parallel flanges 204 and 206 extending upwardly from the I beam 208. A fin 210, secured to the header 162, is positioned between these flanges. Fig. 3 indicates refractory blocks 212 which may be secured to the wall tubes 180. These blocks may be "Bailey blocks," constructed of metal, and tightly secured to the tubes with a thermal bond between the blocks and the tubes, or alternatively, may consist of a stud tube construction in which metallic studs are welded to the tubes and thereafter covered with refractory material and installed as a plastic. Similarly, the gas distribution baffle 50 shown in Fig. 4 of the drawings may be constructed of preformed blocks secured to the tubes, or may be of stud tube construction as above indicated.

What is claimed is:

1. In a water tube steam boiler, an organization including a plurality of upper drums connected to a lower drum by front and rear banks of steam generating tubes, a furnace, means for directing the furnace gases transversely of the drums and through a first gas pass at one side of the boiler, said means including an upright wall extending substantially across one of said banks from front to rear, baffle means including a similar wall and forming a second gas pass in which the gases pass from the outlet of the first pass reversely of their movement in the first pass and forwardly transversely of the tubes of a rear bank, and a superheater positioned in said first pass rearwardly of the tubes of the front bank so as to be screened thereby, the front bank being spaced forwardly of the superheater throughout its length and forwardly of the foremost part of said baffle means and upright wall so as to form a gas equalization chamber.

2. In a water tube steam boiler having a plurality of banks of steam generating tubes connecting a lower drum to a plurality of parallel upper drums, a boiler setting, a furnace including a combustion chamber, means forming a first gas pass positioned at one side of the setting and extending transversely of the drums and tubes and communicating with said chamber at one side of the boiler only, a superheater positioned in said gas pass and screened by the tubes of one of said banks, means forming a second gas pass communicating with the outlet of the first and directing the gases in a reverse direction transversely of said tubes, a partition extending between said banks of tubes forward of the end of the second gas pass and so associated with said first means as to compel gases to pass from the furnace through the first gas pass, one of said banks of tubes extending entirely across the boiler and spaced forwardly of the superheater and said partition so as to afford a gas equalization space, and means associated with the tubes of the last named bank for equally distributing gases passing across the tubes of said bank.

3. In a superheater, a primary section subjected to heating gases at high temperatures operating on the counterflow principle, a parallel flow

section subjected to the same heating gases after their temperature has decreased due to contact with the primary section, means connecting said sections so that a fluid in the sections passes to the parallel flow section from the primary section, and means providing for increased mass flow of the gases over the parallel flow section.

4. In a water tube steam boiler of the Stirling type, a boiler setting, a lower drum, upper drums, upright front and rearward banks of steam generating tubes connecting the drums, a transverse baffle extending from the lower drum to an upper drum transversely of the setting rearwardly of and spaced from the front bank; upright longitudinal baffles so extending relative to a rearward bank and so cooperating with the setting walls and the transverse baffle as to form a plurality of serially connected gas passes the inlet of which leads from the gas space rearwardly of the front bank of tubes and is confined to one side of the setting toward one end of a drum, a furnace from which the gases are distributed across the front bank, said transverse baffle extending substantially at right angles to the longitudinal baffles, and a gas distribution baffle extending across the front bank with a gas contacting surface which diminishes from the wide end of the baffle directly in front of the inlet to the first of said passes to its narrow end near the opposite side of the front bank.

5. In a cross flow water tube boiler, a boiler setting, spaced front and rear banks of steam generating tubes exposed externally to high temperature furnace gases, means for connecting said banks of tubes into boiler circulation, there being a gas equalization chamber rearwardly of the front bank with reference to gas flow, a transverse baffle positioned rearwardly of said chamber and forwardly of said rear bank of tubes, said baffle extending only part of the way across the setting and terminating at the side of the first of a plurality of gas passes leading rearwardly and then forwardly across the rear bank, a longitudinal baffle extending transversely of and joining the first baffle along one side of the first gas pass, means defining a furnace gas chamber forwardly of the front bank of tubes, means providing a gas outlet remote from the first gas pass laterally of the setting, said baffles being supported and cooled by said tubes, and a superheater disposed rearwardly of the front bank of tubes and having tubes extending across the entrance to the first gas pass.

6. In a water tube steam generator, a plurality of upper drums, a submerged drum, a plurality of separated banks of steam generating tubes connecting the upper drums to the submerged drum, downcomers directly connecting the front upper drum with the submerged drum and disposed in a gas pass of the generator, and baffle means causing furnace gases to pass over said tubes in a plurality of gas passes before contacting with the downcomers.

7. In a water tube steam boiler of the Stirling type, means forming a plurality of steam and water chambers, means forming a water chamber below the steam and water chambers, front and rear banks of steam generating tubes connecting the submerged chamber to the other chambers, a furnace, downcomers connecting the front steam and water chamber to the submerged chamber, and baffles forming a plurality of gas passes and directing the gases over said banks of steam generating tubes before the gases contact with the downcomers.

8. In fluid heat exchange apparatus, a furnace, a bank of spaced tubes extending across the path of the furnace gases, means forming an unobstructed gas flow equalization chamber substantially coextensive with said bank of tubes and disposed on the side of said bank opposite the furnace, means forming a gas pass directly communicating with said chamber over only a fraction of the horizontal width of the chamber and

the furnace with the furnace gases passing over said tubes and through said chamber to the entrance of the gas pass, means forming additional heating surface in the gas pass, a part of said bank of spaced tubes positioned directly forwardly of said entrance while the remainder of the bank extends laterally in a horizontal direction beyond the entrance and in front of said chamber. 5

PERRY R. CASSIDY.
